US0D1044831S

(12) **United States Design Patent** (10) **Patent No.:** **US D1,044,831 S**
(45) **Date of Patent:** **** Oct. 1, 2024**

(54) **DISPLAY SCREEN OR PORTION THEREOF WITH GRAPHICAL USER INTERFACE**

(71) Applicant: **HUAWEI TECHNOLOGIES CO., LTD.**, Guangdong (CN)

(72) Inventors: **Chenyang Mao**, Shenzhen (CN); **Jinsong Guo**, Shenzhen (CN)

(73) Assignee: **HUAWEI TECHNOLOGIES CO., LTD.**, Shenzhen (CN)

(**) Term: **15 Years**

(21) Appl. No.: **29/836,812**

(22) Filed: **Apr. 29, 2022**

(30) **Foreign Application Priority Data**

Nov. 3, 2021 (CN) 202130722569.X

(51) **LOC (14) Cl.** **14-04**

(52) **U.S. Cl.** ..... **USPC** **D14/488**

Primary Examiner — Rachel A. Voorhies

(57) **CLAIM**

The ornamental design for a display screen or portion thereof with graphical user interface, as shown and described.

DESCRIPTION

FIG. 1 is a front view of a first embodiment of a display screen or portion thereof with a graphical user interface showing our new design; and,

FIG. 2 is a front view of a second embodiment of a display screen or portion thereof with a graphical user interface showing our new design.

The outermost dash-dot broken lines in the drawings illustrate the display screen or portion thereof and form no part of the claimed design. The other dotted broken lines in the drawings illustrate portions of the graphical user interface that form no part of the claimed design.

1 Claim, 2 Drawing Sheets
